UNITED STATES PATENT OFFICE

99,726

DESIGN FOR A TABLE

Dwight Powell, Youngstown, Ohio, assignor to
The General Fireproofing Company, Youngstown, Ohio, a corporation of Ohio

Application April 3, 1936, Serial No. 61,933

Term of patent 14 years

To all whom it may concern:

Be it known that I, Dwight Powell, a citizen of the United States, residing at Youngstown, in the county of Mahoning and State of Ohio, have invented a new, original, and ornamental Design for a Table of which the following is a specification, reference being had to the accompanying drawing, forming part thereof:—

The figure is a perspective view of a table showing my new design.

I claim:—

The ornamental design for a table as shown.

DWIGHT POWELL.
